[57] CLAIM

The ornamental design for a combined blanket and bag, as shown and described.

DESCRIPTION

FIG. 1 is a top view of a combined blanket and bag showing our new design;

FIG. 2 is a bottom plan view thereof;

FIG. 3 is a left side elevational view thereof, the right side being identical;

FIG. 4 is a front elevational view thereof, the rear being identical;

FIG. 5 is a perspective view thereof in a closed position;

FIG. 6 is a side elevational view of FIG. 5, both sides being identical therefor.

It is understood that the drawings are shaded to show fabric and the pattern continues and repeats uniformly across the entire surface of the claimed design. One side is shaded to show smooth fabric, the opposite side showing a roughened fabric.
